UNITED STATES PATENT OFFICE

166,481

GOBLET OR SIMILAR ARTICLE

William P. Morrison, Mount Pleasant, Pa., assignor to Bryce Brothers Company, Mount Pleasant, Pa., a corporation of Pennsylvania

Application March 28, 1951, Serial No. 14,649

Term of patent 14 years

(Cl. D36—8)

To all whom it may concern:

Be it known that I, William P. Morrison, a citizen of the United States, residing at Mount Pleasant, county of Westmoreland, in the State of Pennsylvania, have invented a new, original, and ornamental Design for a Goblet or Similar Article, of which the following is a specification, reference being had to the accompanying drawing, forming a part hereof.

Figure 1 is a side elevational view of a goblet or similar article, showing my new design;

The dominant features of the design reside in the portions drawn in full lines, as shown.

I claim:

The ornamental design for a goblet or similar article, as shown and described.

WILLIAM P. MORRISON.
